UNITED STATES PATENT OFFICE

EDGAR SCOFIELD, OF NEW YORK, N. Y., ASSIGNOR TO ANCHOR CAP & CLOSURE CORPORATION, OF LONG ISLAND CITY, NEW YORK, A CORPORATION OF NEW YORK

SEALED PACKAGE AND PARTS THEREOF

Application filed May 16, 1927. Serial No. 191,663.

The present invention relates to the sealing art and more particularly to a sealed package and the parts thereof.

Heretofore in the sealing art various types of closure caps have been used to seal food products and the like. The caps which form the most secure hermetic seals generally adhere so effectively to the containers that they are mutilated in their removal and are not suitable for resealing. Hence the consumer permits the contents of the package to remain exposed to the atmosphere and impurities while it is being used. Naturally this is undesirable and many packers use the much less effective and less efficient screw cap solely for the reason that it may be re-sealed indefinitely. Other packers have applied covers over the containers beneath the usual closure caps. With such covers as well as with screw and other re-seal caps, the interior and sometimes the exterior portions become contaminated with the contents of the container and are accordingly sticky and unsightly.

The present invention overcomes these difficulties by providing a separate cover cap adapted to be nested over the usual closure on a container and to be removed and used as a cover for the container. The cover cap being mounted exteriorly of the container does not become contaminated with the contents thereof. Further its being nested over the usual closure cap gives the package the appearance of having a deep skirt cap which is more desirable in the trade. This is particularly beneficial with caps having narrow skirts.

An object of the invention is to increase the depth of narrow flange caps without lowering the position of the seal on the containers and without increasing the head space of the containers.

Another object of the invention is to provide a cover cap adapted to be frictionally attached to the upper part of a closure cap to improve the appearance thereof and at the same time to serve as a cover for the container when the closure cap is removed.

Another object of the invention is to provide a cover cap having a resilient skirt 50 adapted to size itself to the upper part of the

closure cap and also to the outer side wall of a container.

Another object of the invention is to provide an effective cover cap which may be readily attached to the present form of packages without detracting from the appearance thereof to serve as a cover for the container after the closure cap is removed. 55

Other and further objects of the invention will be obvious upon an understanding of the illustrated embodiment about to be described and various advantages not referred to herein will occur to one skilled in the art upon employment of the invention in practice. 60

A preferred embodiment of the invention has been chosen for purposes of illustration and description and is shown in the accompanying drawings, wherein

Fig. 1 is a side elevational view of a package with the cover cap in place; 70

Fig. 2 is a sectional view of one form of cover cap;

Fig. 3 is a bottom view of the cover shown in Fig. 2; 75

Fig. 4 is an enlarged fragmentary view, showing the position of the cover cap with respect to the closure;

Fig. 5 is a sectional view of another form of cover cap; and 80

Fig. 6 is a perspective view of the elements in unassembled position.

Referring to the drawings there is shown a container 1 which may, for convenience, have an annular cylindrical sealing zone 2 adjacent its upper end. A closure cap 4 having a bead 5 in the skirt thereof, is mounted upon the container with the bead deformed to press a gasket therein against the side wall of the container to effect a hermetic seal. 85 The upper part of the bead 5 forms with the skirt of the cap a shelf 6 which facilitates the application of a cover cap 7.

While various forms of cover caps may be used, there is shown in Fig. 5 one form having a cover portion 8 and a depending skirt 9 terminating in a wire edge 10 at the bottom thereof. The skirt of the cap is preferably flared slightly to facilitate its application to the upper part of the closure cap and to facilitate 100

tate also its application to the container after the closure cap is removed, since the external dimensions of the closure cap and container differ slightly.

5 The form of cover cap shown in Figs. 2 and 3 is corrugated substantially the entire length of the skirt and does not have a wire edge at the bottom thereof. The corrugations 11 permit the skirt to expand readily to a limited 10 extent. This facilitates the application of the cap both to the closure cap and to the container since it will size itself readily to these.

15 Preferably the covers are sufficiently small to nest over the upper portion of the closure cap and extend substantially down to the shelf 6, leaving a sufficient space to permit the application of a tool or of a coin to pry the cover from the closure cap. Since the 20 closure cap must be telescoped over the mouth of the container, it must be slightly larger than the container. The cover cap being nested over the closure cap is necessarily substantially larger than the external 25 dimension of the container. By providing the readily yieldable skirt and sizing it so that the cover goes only partially down on the closure cap, its removal is facilitated and its size is more nearly that of the container. In 30 this manner the cover may be properly sized to both the closure cap and the container.

35 The packages are sold with the three elements of the package in assembled relation as shown in Fig. 1. The consumer pries off the cover cap and thereafter removes the closure cap and replaces it by the cover which protects the contents of the container against impurities while the food is being consumed. The height of the skirt of the cover cap adds 40 to the apparent depth of the closure cap and gives the appearance of a deep skirt cap which is more attractive than the narrow skirts heretofore used.

45 It will be seen that there has been provided a cover cap inexpensive in construction and readily manufactured from commercial materials and that the cover may be attached to packages now on the market without detracting from the appearance thereof. It is readily sizable to both the closure cap and container without danger of accidental removal during shipment or in use.

55 As various changes may be made in the above embodiment without departing from the spirit of the invention, it is to be understood that all matter herein is to be interpreted as illustrative and not in a limiting sense.

Having thus described my invention, I 60 claim:

65 1. A sealed package comprising a container, a closure cap having a bead in the skirt thereof forming an annular flange, a gasket in the bead sealed to the outer side wall of said container and a cover cap frictionally at-

tached to said closure cap above said bead and adapted to increase the height thereof.

2. A sealed package comprising a container, a closure cap hermetically sealed to the outer side wall of said container, the upper portion of said closure cap being tapered upwardly, and a cover cap adapted to rest on and be frictionally secured to the tapered part of said closure cap and to frictionally engage the side walls of the container thereby to provide a cover for the container after the closure cap is removed. 70 75

3. As an article of manufacture, a closure cap having the upper portion thereof tapered or of diminishing diameter, and a cover cap 80 attached to the tapered part of the closure cap to improve the appearance thereof and to furnish a cover for a container after the closure cap is removed.

4. As an article of manufacture, a closure 85 cap and a cover cap attached thereto to improve the appearance thereof and to furnish a cover for a container after the closure cap is removed, said cover cap having a readily expansible skirt to fit above the upper part 90 of the closure cap and also about the side wall of the container.

5. As an article of manufacture, a closure cap having a relatively narrow skirt, a cover cap telescoped thereover and secured to the 95 closure cap to give the effect of a deep skirt, said cover being corrugated to expand or contact to proper size to fit upon the container when the closure cap is removed.

6. As an article of manufacture, a closure 100 cap having a relatively narrow skirt, a cover cap telescoped thereover to give the effect of a deep skirt, said cover cap having a corrugated skirt to give maximum resilience and to permit said cover cap to fit about the upper 105 portion of the closure cap and also about the mouth of the container.

7. As an article of manufacture, a cover 110 cap comprising a cover portion and a depending skirt, said skirt being corrugated throughout its length to facilitate expansion thereof and to provide a snug fit on a suitable closure cap and also on a container, the closure cap and container differing substantially 115 in size.

8. A sealed package comprising a glass container, a closure cap sealed thereon having a relatively narrow skirt, a cover cap nested about said closure cap to give the effect of a deep skirt, said cover cap being corrugated 120 to adapt it to fit snugly the upper portion of the closure cap and to fit also the side wall of a container.

9. A sealed package comprising a container, a closure cap sealed thereon having a relatively narrow skirt, a cover cap nested about said closure cap and secured thereto to give the effect of a deep skirt, said cover cap being adapted to size itself to a container 125 when the closure cap is removed. 130

10. A sealed package comprising a container, a closure cap having an annular shelf or shoulder in the skirt thereof, a cover cap adapted to fit over said closure cap with the lower edge thereof spaced from the shelf to facilitate application of a suitable tool for the removal of the cover cap.

11. A sealed package comprising a container, a closure cap sealed to said container, and a cover cap mounted on said closure cap having a minimum diameter greater than the maximum diameter of the container, said cover cap being adapted to provide a cover when said closure cap has been removed from the container.

12. A sealed package comprising a container, a closure cap sealed to said container, and a cover cap mounted resiliently on said closure cap having maximum diameter smaller than the maximum diameter of said closure cap.

13. A sealed package comprising a container, a closure cap sealed to said container, and a cover cap mounted on said closure cap having a minimum diameter greater than the maximum diameter of the container and a maximum diameter smaller than the maximum diameter of the closure cap.
